US0D1081649S

(12) **United States Design Patent** (10) **Patent No.:** **US D1,081,649 S**
(45) **Date of Patent:** **** Jul. 1, 2025**

(54) **AI FACE TRACKING SELFIE STICK**

(71) Applicant: **Shenzhen Zandian Technology Co., Ltd**, Shenzhen (CN)

(72) Inventor: **Shenghui Liao**, Shenzhen (CN)

(**) Term: **15 Years**

(21) Appl. No.: **35/519,998**

(22) Filed: **Dec. 12, 2023**

(80) **Hague Agreement Data**

Int. Filing Date: **Dec. 12, 2023**

Int. Reg. No.: **DM/235044**

Int. Reg. Date: **Dec. 12, 2023**

Int. Reg. Pub. Date: **Feb. 16, 2024**

(30) **Foreign Application Priority Data**

Jun. 17, 2023 (CN) 202330375418.0

(51) **LOC (15) Cl.** **16-05**

(52) **U.S. Cl.**

USPC **D16/244**

(58) **Field of Classification Search**

USPC D14/251-253; D16/237, 242-244

CPC G03B 15/041; H04M 1/12; F16M 11/28

Primary Examiner — Rebekah A Caruso

(57) **CLAIM**

The ornamental design for an AI face tracking selfie stick as shown and described.

DESCRIPTION

1.1: Perspective view

1.2: Front view

1.3: Back view

1.4: Left view

1.5: Right view

1.6: Top view

1.7: Bottom view

1.8: Perspective in an unfolded state

1.9: Front in an unfolded state

1.10: Back in an unfolded state

1.11: Left in an unfolded state

1.12: Right in an unfolded state

1.13: Top in an unfolded state

1.14: Bottom in an unfolded state

1.15: Enlarged view

1.16: Enlarged view

1.17: Enlarged view

The parts shown by means of broken lines in the reproductions are not part of the claimed design.

1 Claim, 17 Drawing Sheets
